WRINGER

Albert R. Haag and George A. Haag, Peoria, Ill.

Application October 30, 1939, Serial No. 302,020

5 Claims. (Cl. 68—253)

This invention pertains to improvements in wringer structures, having to do particularly with a novel manner of instantly releasing the pressure between the wringer rolls.

The main object of the invention is to provide a very simple means of bringing about the release of the upper wringer-roll in which a minimum of elements will be involved thus eliminating complications and producing a more positive release action.

Another object is to furnish in combination with a clutch mechanism a simple control arrangement directly engaged by the usual top closure-portion by which said clutch mechanism can more positively function.

Still another object is to employ the fewest number of parts in a clutch control arrangement in order that there will be less chance for wear between parts or misadjustment of said parts such as would lead to inaction at a critical moment.

To the end that the invention may be fully understood, the accompanying drawings are provided forming part hereof.

Figure 1 is a side elevation of a wringer constructed according to the present invention;

Figure 2 is an enlarged transverse sectional elevation of the structure of Figure 1 produced on line 2—2 of that figure;

Figure 3 is an elevation, also enlarged, of part of the wringer body as viewed from the left of Figure 1;

Figure 3^a shows a cam in perspective;

Figure 4 is a longitudinal section of a gear box portion of the wringer structure, produced on the same scale as Figures 2 and 3;

Figure 5 is a transverse elevation of parts of a gear control structure produced on line 5—5 of Figure 4;

Figure 6 is a plan of parts shown in Figures 4 and 5 produced on line 6—6 of the last named figure;

Figure 7 is an end elevation of a portion of the wringer body as viewed at the right of Figure 1, parts being shown in section;

Figure 8 is a plan of a control mechanism shown in Figure 7 produced on line 8—8 of that figure, together with parts shown in Figure 6, and

Figure 9 is a reproduction of parts shown in Figure 8.

The invention forming the subject of this application is somewhat along the lines of the invention of pending application of Albert R. Haag, Frank W. Werckle and Ross E. Locher, Wringers,

filed under date of November 4, 1937, Serial No. 172,819 but differs therefrom in that control means for the wringer-roll drive is directly influenced by the top closure portion of the wringer as a simplified structure for producing very positive results.

In the drawings hereof 1 denotes the wringer frame, 2 a top closure portion, and 3 and 4 a lower and an upper wringer roll respectively, the usual gear box being indicated at 5.

In the present instance the closure portion 2 is hinged to the frame 1 at one side thereof but, perhaps may be otherwise controlled.

The shafts of the wringer rolls 3, 4 have their bearings in blocks 3', 4' respectively, Figure 2, said blocks being slidable in guide ways 6 created between opposed walls 7, Figures 1 and 2 in much the usual manner, the shaft 8 of the lower roll 3 extending into the gear box 5 and having slideable thereon but rotatable therewith a pair of gears 9, 10 fixed relatively.

Any usual power shaft is indicated at 11 and carries a gear 12 within the gear box, either of the gears 9, 10 being adapted to separately mesh with the said gear 12 in the well known way.

Suspended above the gears is a cam 13 mounted to rotate with a shaft portion 14 thereof.

Depending from the upper wall of the gear box, in this instance, is a bearing 15 within which the said cam 13 is rotatable. The cam as at present constructed is for the most part cylindrically formed in order to rotate in said bearing but is recessed at 16, Figures 3^a, 4, 5 and 6.

At the bottom of the recess are three faces 17, 18, 19, the two latter, 18 and 19 each lying at an angle, in this instance of substantially 45° to the face 17, the several faces otherwise substantially paralleling the axis of cam rotation. The shaft portion 14 is axially coincident with the wringer shaft 8, Figure 5, and beneath the cam is suspended a slide 20 by means of an extension 21 of the former which is eccentric to the said shaft portion 14, said slide engaging in a groove 22 of the gears 9, 10, being slideable in said groove in a direction naturally paralleling the faces of said gears.

Slidable in a bore 1' of that wall of the wringer frame 1 adjacent the gear case, and slideable also in an extension of the bearing 15 is a member or rod 23. One end of said rod is adapted to abut any one of the faces of the cam 13, while in and near the other end at the said wall of the frame 1 the rod has a recess, preferably a groove 24. A coil spring 23' encircles the rod which is under compression between the named wall of

the frame 1 and a pin 23², for example, carried by said rod, by which the latter is normally urged in the direction of the cam 13.

As shown in Figures 7 and 8 the named wall of the frame 1 is provided with a bore 25 said bore opening into the bore 1' and also opening upon the top surface of the frame 1 whereon is received the top closure portion 2. Slidable in the bore 25 is a pin 26 and between the latter and the bore 1' is spring 27 and a ball 28, the latter adapted to either abut upon the rod 23 or to engage in the groove 24 thereof.

In either position of engagement of the ball the spring 27 is under compression and thereby the pin normally extends above the said top surface of the frame. Any conventional means may be employed to retain the pin within the said bore 25.

Clearly, upon closing the top portion 2 its under surface will engage and depress the pin 26 against the tension of the spring 27, while also placing pressure upon the upper roller 4 as now to be seen.

The said top portion includes in this particular instance, a flat spring 28', the ends of the springs being guided between ears 29 of said portion and resting upon cross pins 30 carried by the latter, Figures 1, 2 and 3. The spring 28' is illustrated as secured to the top 2 by a conventional rivet passing through the spring at about the middle point of its length, but the exact manner of securing for the spring to the top cover does not comprise any part of the present invention. In Figure 2 the upper wringer-roll bearing 4' is shown as extending to a position to receive the end of the spring 28' thereon, said spring exerting pressure on the upper roll when the top portion is in abutment with the frame-top.

Latching means is comprised, in this case, in a shaft 31 journaled in the top portion and extending throughout the length thereof, each end of the rod having affixed thereto a latch 31', one of them including an upstanding handle portion 32, said latches adapted each to engage beneath a cam-part 33 of the frame 1.

In referring to Figure 8 the face 19 of the cam 13 is shown in a position of unrest in dotted lines. That is to say, it is noted that the rod 23 due to the spring 23' is being urged toward said cam and rests against a part of a face thereof that lies in a position eccentric to the center of cam rotation. In such a position of the cam that member would be rotated toward the left until said rod comes into abutment with the face 17 as illustrated in continuous lines as the normal position of the parts, the broken lines position being maintained by controlling the rod 23 by the pin 26 already described as will now be more fully set forth.

When the top portion 2 is unlatched and therefore not depressing the pin 26 the rod 23 is free to shift lengthwise by and through hand actuation of the cam 13, the spring 23' upon the release of the cam however, carrying the latter to the position shown in Figures 4, 6 and 8 as before stated as the normal position of the said cam, and at the time the gears are in neutral.

Now, upon closing the top portion and latching it the pin 26 has been depressed forcing the ball 28 toward and upon the rod when the latter has the position shown in Figure 8. By turning the cam to bring about the meshing of either of the gears 9, 10 with the power-driven gear 12 the slide 20, through the swing of the extension 21

of the cam in the direction chosen, and at the same time a cam face 18, 19, corresponding to the gear chosen, meets and shifts the rod 23 against the tension of its spring 23' with the result that the groove 24 is carried beneath and opposite the spring held ball 28 wherein the latter enters, Figure 10, its entry thus maintaining the engagement of the gears selected.

Instant release of the gears is accomplished by striking the latch handle 32 to disengage the latches 31' from the cam 33 whereupon the spring 28' in the top portion 2 exerts itself to lift said portion releasing the top roll 4 and permitting the pin 26 to release pressure on the ball within the groove 24. The spring 23' on the rod 23 is strong enough to force the ball from the groove the said rod acts upon the cam face upon which it has been resting to swing the cam and disengage the gears.

The invention contemplates the use of any other convenient part of the wringer structure for depressing and releasing the pin 26. That is to say, the invention is not confined to the employment of a part of the top portion 2 necessary for the purpose named.

Changes may be made in the structure such as may be considered to fall within the claims to follow.

What is claimed is:

1. In combination with a wringer structure including a liftable top closure, wringer rolls, a power gear, and a pair of shiftable gears for selectively engaging said power gear, of a manually operated cam having a plurality of faces and having associated therewith a crank slide operatively engaging the pair of gears for selective meshing thereof with the power gear, a rod elastically held at one end in engagement with the cam, and shiftable lengthwise by the latter, a first means in the path of movement of the rod, means to urge said first means elastically into engagement with the rod, said first means and rod being fashioned to interlock one with the other for holding the rod in an extreme position when the named gears are in mesh, said first means lying in position to be moved toward the rod by contact of a part of the top closure therewith.

2. The combination with a wringer structure including a liftable top closure portion, wringer-rolls, a power gear, and a pair of shiftable gears for selectively engaging the said power gear, of a manually controlled cam and having associated therewith a crank slide operatively engaging the shiftable gears for selectively meshing them with the power gear, a shiftable member at one end, elastically abutting the cam, means to elastically engage the member to secure it in a fixed position when the gears are in mesh, said means being engaged by a part of the said closure portion when in its closed position to effect such fixing of position of the said member, said means being released by lifting movement of the closure to release the member, said cam having a portion eccentric to the axis of cam rotation against which the member abuts, said member upon its release operating the cam to disengage the gears by means of said crank slide.

3. The combination with a wringer structure having a spring lifted top closure and a latch therefor, a power gear, and a pair of shiftable gears for selective engagement with said power gear, a rotatable cam and having associated therewith a crank slide operatively engaging the gears for shifting them in one direction by man-

ual control, said cam having a face eccentrically positioned with respect to its axis of rotation, a member elastically held against said face during meshing of the gears, and including a recess, means stationed between the top closure and the member and elastically held in locking engagement in the recess of the latter by said closure, said means being released from the member by operation of the latch of the closure, said member when released operating the cam to disengage the gears by means of said crank slide.

4. In a wringer structure in combination with a wringer frame including a top closure, a first means to elastically unseat the latter, and a releasable latch for said closure, a power gear, and a pair of gears, a second means adapted to swing for shifting and selectively meshing the gears with said power gear and having a portion disposed in spaced relation to the point about which said second means swings, a member elastically abutting the portion when the gears are in mesh and constantly tending to swing the said second means to bring about disengagement of the gears, and elastically controlled detent means between the member and the closure, said closure in its seated position on the wringer frame forcing said detent means into engagement with the member for securing the same in fixed position during

meshing of the gears, said member being releasable from the control of said elastically controlled detent means by the opening movement of said top closure, said member when released acting to swing said second means to bring about disengagement of said gears.

5. In combination with a wringer structure including wringer rolls and a frame therefore, a power gear, and a pair of shiftable gears for selectively engaging said power gear, of a manually operated cam having a plurality of faces and having associated therewith a crank slide operatively engaging said pairs of gears for selective meshing thereof with the power gear, a rod yieldably held and having one end in engagement with said cam and shiftable lengthwise by the latter, a first means in the path of movement of said rod, means to urge said first means yieldably into engagement with said rod, said first means and rod being fashioned to interlock one with the other for holding the rod in an extreme position when said gears are in mesh, said first means extending to a position beyond said frame so that said first means is accessible to receive pressure lengthwise thereof whereby it may be moved toward said rod.
